E. ALLEN

PROPELLER SHAFT BEARING

Filed Feb. 17. 1921

Patented Oct. 21, 1924.

1,512,261

UNITED STATES PATENT OFFICE.

EDWARD ALLEN, OF JERSEY CITY, NEW JERSEY.

PROPELLER-SHAFT BEARING.

Application filed February 17, 1921. Serial No. 445,697.

To all whom it may concern:

Be it known that I, EDWARD ALLEN, a resident of Jersey City, in the county of Hudson and State of New Jersey, have invented certain new and useful Improvements in Propeller-Shaft Bearings, of which the following is a specification.

This invention relates to improvements in stern tube bearings for propeller shafts, and is directed more especially to means for sealing the ends of such tubes.

It is the usual practice to house out board or tail propeller shafts within a stern tube provided interiorly with longitudinally extending strips of lignum vitæ, which space the shafts from the tubes and provide a smooth bearing for the former in the outer portion of the latter. The after ends of such tubes are ordinarily left open, permitting the sea water to enter between the strips and circulate thruout the lengths thereof, particularly when they have become worn. This is done upon the assumption that the water will assist in lubricating the shafts rubbing on the strips, keep down friction and carry off the heat generated. Besides in view of the fact that salt water in particular has a detrimental corrosive effect on the shafts, the same are generally lined or surrounded by endwise abutting brass or bronze sleeves.

The construction above noted is not only expensive, but allows sand and grit to work into the ends of the stern tubes, especially when operating in shallow waters, where the screw or propeller stirs up the sea or river bottom. The action is most pronounced when the rotation of the screw is reversed, since backward turning of the propeller manifestly throws the muddy water directly against the after end of the stern tube and causes the sand and grit to find their way in between the bearing strips and the shaft liners.

The presence of grit among these parts rapidly wears them out so that after a while the propeller shaft works so loosely that it is practically unsupported at the aft end thereof, causing it to sag at the tail portion.

This condition is manifested by the knocking or thumping sound often heard at the stern of a propeller driven steamer.

When a tail shaft is operated without proper support, as a result of the wear referred to, whipping of the shaft ensues, and the strains occasioned thereby are so severe

that they ultimately cause fracture or breaking of the shaft. In the case of a single screw boat working in heavy seas, at which times such accidents generally occur, the 60 breakage of a propeller shaft is apt to have serious consequences, since the vessel then loses headway and becomes unmanageable.

Furthermore, the sagging or bending of the shaft has the effect of opening up the 65 joints between the liners or sleeves allowing the sea water to attack and cause pitting of the shaft. This deleterious condition is accentuated by electrolytic action taking place between the steel shaft and the copper alloy 70 of the liners, particularly when they are subjected to the influence of salt water.

In order to keep the sea water that has entered the stern tube from leaking thru the inner end thereof, a stuffing box packed 75 with hemp is mostly used for this purpose. But as such packing generally becomes hard when exposed to salt water and loses its flexibility, the stuffing box gland has to be tightened up frequently. This forces the 80 stiffened packing still harder against the surface of the shaft, which thru continued usage is badly cut or scored thereby.

The present invention aims to obviate the 85 above enumerated difficulties, as also others, and the main or primary object thereof is to provide an effective seal for the ends of a propeller shaft bearing or stern tube, which will prevent the entrance thereinto of muddy or grit-carrying water, as well as retain 90 therein the substance employed to lubricate the shaft.

Another object is to produce a device of the character described wherein the lubricant used has free access to the working surfaces of the stern bearing thruout the entire 95 length thereof without permitting the lubricating matter to escape at either the inner or outer end of the tube, whereby an economical use of such matter is gained.

A further object is the provision of a device of the nature set forth in which the contacting pressure between the elements which effect the sealing of the ends of the stern tube is controlled by a lubricant supplied from within the vessel.

Still another object in the production of a device of the type specified is to dispense with the liner sleeves heretofore associated with tail shafts of propellers, as well as to 110 avoid their attendant disadvantages, and to accomplish this result without exposing such

shafts to the corrosive action of sea water.

A still further object in producing a device of the class mentioned is so to arrange the co-operating members thereof that the overhang of the propeller from the stern tube may not be increased materially beyond what is accepted in common practice.

An additional object is to procure a device of the species referred to entirely devoid of springs, and so constructed that the coacting elements are self-adjusting without undue pressure thereon and will retain a tight running fit for the propeller shaft while obviating scoring or cutting of the same.

A general object is to supply a device of the genus alluded to composed of a minimum number of parts, simple, durable and amenable to low cost of manufacture, as also expeditiously assembled or dismantled, besides capable of being readily applied to existing stern tubes without appreciable alteration thereof.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

In the said drawing:

Figure I is a sectional elevation of a part of the stern of a propeller driven vessel showing the usual tubular bearing thereof with this improved sealing device applied to the ends of the same;

Fig. II is an enlarged end view of an element forming part of the present device;

Fig. III is a similar view of another element employed in this construction;

Fig. IV is a like view, of an additional element adapted to be associated with the one illustrated in Fig. II; and

Figs. V and VI are transverse sections on the lines V—V and VI—VI respectively, of Fig. I.

Succinctly outlined, the device under consideration includes in its organization a cap member secured in any appropriate manner to either end of the usual stern tube which houses the propeller tail shaft. The cap that is attached to the outboard end of the stern tube is provided with a boss adapted to extend into and be received in a recess formed in the adjacent face of the hub of the propeller, the shaft of the latter passing thru the cap and its boss with a snug turning fit. Seated within the cap, spaced from the end of the tube, is a follower element fitting around the shaft relatively tight and

arranged to be rotated thereby, but capable of restricted axial movement with respect to the same. The follower consists preferably of outer and inner parts, of which the one last named is in the nature of a split packing ring wedgingly engaged by the outer part, while both of them bear against the inside head of the cap member. The construction is such that the more the outer part is forced out endwise, the harder the inner part will grip the shaft so as to prevent any leakage between the latter, the cap and the parts themselves.

Lubricant preferably heavy grease, is introduced under pressure into the stern tube by any suitable means, such as a force-feed grease-cup, and caused to fill up the interstices between the bearing strips and the bushings. The pressure of the lubricant exerted upon the follower forces the latter against the inside head of the cap and effects a seal therewith so that very little or no lubricant can pass the same, nor between the periphery of the follower and the cap. The grease thus supplied, not only lubricates the shaft and the stern bearings, but in its attempt to find an exit thru the closure at the after end of the tube, automatically operates to effect a seal for the same and precludes the entrance of sea water thereinto. In practice, a small amount of the lubricant may work its way out, but the loss thereof is negligible.

The member at the inboard end of the stern tube comprises a discoidal plate, hollowed out to receive the follower element which is driven and acts in a manner similar to that at the outer extremity of the tube. This plate or retaining member may be held in its assigned position by the same bolts that were used to draw up the gland against the packing in the stuffing box. Due to this construction no scoring or cutting of the shaft can occur at the place mentioned, and the lubricant is also prevented from leaking out. The space formerly occupied by the packing will constitute a reservoir for the grease which will fill the same. Thus it will be seen that the entire part of the tail propeller shaft housed within the stern tube runs in a bath of grease which in its turn prevents the entrance of water into the former.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted

merely as showing the preferred exemplification of the invention.

Referring now to the aforesaid views of the drawing for a detail description of the invention, the known elements of a stern tube or tail shaft bearing, and the parts with which the same are associated have been designated by reference letters, of which A denotes the stern post of a vessel, which post has the usual rearwardly extending frame B forming therewithin the propeller well C.

From a point interiorly of a bulkhead D there runs in a fore and aft direction thru the stern post, the stern tube E, the outer extremity whereof terminates within the propeller well. The said stern tube is necked down as at E¹ so as to provide a shoulder E² arranged to abut the forward edge of the stern post. The necked down portion of the tube E reaching within the well C is furnished with a threaded part E³ adapted to receive a nut E⁴ wherewith the shoulder E² can be firmly drawn up against the stern post.

Near its inner end, the stern tube is formed with a flange E⁵ thru which it is supported from the bulkhead D, being secured thereto as by screw bolt E⁶. At the innermost extremity, the stern tube has as ordinarily is the case, a flange E⁷ from which project stud bolts E⁸ adapted to retain in position the customary stuffing box gland (not shown).

In conformity with current practice, and varying more or less, according to circumstances approximately one-half the length of the interior of the stern tubes inboard portion is provided with brass or bronze bearing-bushings E¹⁰ within which is journalled the propeller tail shaft F. The remaining part of the latter which is not carried by these bushings, is instead supported by a plurality of hardwood strips E¹¹, such as lignum vitæ. These strips extend longitudinally of the tube E and are fastened therearound as by dove-tail connections E¹², best seen in Fig. V. The said strips E¹¹ are shaped complementary to the cross-sectional contour of the shaft and engage the rear end thereof so as to form a continuous bearing.

The propeller shaft F projects beyond the after end of the stern tube, into the well C and is tapered as at F¹ to constitute a seat for a correspondingly shaped hole thru the hub of the propeller G. This hub is keyed to the tapered portion F¹ as shown in Fig. I, and the parts are forced solidly together by means of a nut F² which is threaded onto a reduced extreme portion F³ of the shaft and acts against an interposed washer F⁴. Generally, the interstices in the outboard portion F¹ of the shaft, and in the hub of the propeller, as also the con-

tacting faces of the nut F² and washer F⁴, as well as the reduced part E¹ of the tube with the shoulder E² and therewith coacting nut E⁴, are coated and filled in with some such substance as heavy white-lead paint, to preclude corrosion.

Lubricant is introduced into the interior of the stern tube thru a pipe H which connects with the side of the former and leads to any convenient locality within the vessel, at which point it is provided with a force-feed grease cup H¹, or other suitable means for applying pressure onto the grease. In alignment with the outlet of the pipe H, the bearing bushing E¹⁰ has one or more passages H² thru which the lubricant is directed against the shaft F. If desired, the inner surface of this bushing may also be formed with grooves to insure circulation of the grease and effect its traveling toward the stern of the boat. Grease thus injected within the stern tube will entirely fill the same including the spaces that may exist between the strips E¹¹, and in this bath of lubricant the shaft revolves so that it will be properly lubricated at all times and friction reduced.

As hereinbefore mentioned, the ends of the stern tube are sealed each by a suitable mechanism which is preferably operable by the lubricant pressure within the tube to effect a tight seal which will both preclude the leakage of lubricant therefrom as well as the entrance of water thereinto. This mechanism which is the salient feature of the present invention, will now be particularly described.

The reference numeral 15 denotes a cap or retaining member having a shell-like extension 16 adapted to fit over the after end of the stern tube E and firmly affixed thereto as by means of screws 17 or in any other suitable or desired manner. Altho this retaining member has been represented as attached to the exterior of the stern tube, it is within the province of the present invention to secure the same in any other appropriate way.

The outer end of the cap member 15 is extended rearwardly to enclose that portion of the shaft F which would otherwise be exposed between the former and the adjacent face of the propeller hub. With this purpose in view the said cap has projecting therefrom a boss 18 bored as at 19 to let the shaft pass therethru and formed exteriorly so as to fit a complementary recess provided therefor in the forward end of the hub of the propeller G. By this construction it will be manifest that in spite of the fact that the tail end of the propeller shaft is mounted without the employment of liners or external sleeves, as heretofore, sea water has no direct access thereto.

Interiorly the cap 15 is hollowed out to constitute a cylindrical chamber 21 in which is adapted to be seated a follower element 22 of discoidal formation and having a bore 23 fitted to take over the shaft F, being rotated thereby preferably thru a key or spline connection. The latter is shown as consisting of a feather 24 carried by the shaft F and co-operating with a keyway 25 formed at one side of the bore 21 in the follower. Thus, the element 22 is secured against rotation on the shaft, but adapted for slight movement longitudinally or axially thereof, which in the structure illustrated is between an inner head 26 of the retaining member 15 and the end of the stern tube.

With this construction, it will be apparent that the pressure of the grease within the stern tube acts upon the follower 22, thereby causing it to be forced tightly against the head 26 which constitutes a seat therefor and includes both transverse and circumferential surfaces. The force with which the follower engages this seat will obviously be proportionate to the pressure of the lubricant in the tube. Accordingly, a seal will thus be effected which becomes better as the pressure of the grease increases, so that a relatively high pressure of the latter will not result in leakage at this point. However, to insure proper lubrication between the contacting surfaces of the follower and its seat, the former is preferably provided on its outer face with one or more circular grooves 27 which may be intersected by radial channels 28, and at the intersections of said grooves and channels, passages 29 are provided thru the follower in order to permit the grease to circulate and properly lubricate the parts.

With the purpose of precluding leakage of the lubricant past the follower 22 and out thru the bore 19 of the boss 18, the after face of the said follower may be provided with an outwardly flared recess 31 in which is lodged a packing ring 32 preferably split diametrically into two halves that are adapted, collectively to embrace the shaft F. The periphery of this packing ring is bevelled as at 33, and the sections thereof which have a common bore 34 are forced together by the taper of the recess 31 and made to tightly clasp around the shaft. At 35 is indicated a keyway with which one of the ring sections is provided and that is adapted to be engaged by the feather 24. By virtue of this arrangement both the follower 22 and its packing ring are positively rotated by the shaft as well as axially movable thereon, while the former are also interrelatively self-adjusting.

The chief function of the packing ring sections is to act as a barrier against straight thru flow of the grease. This may be fur-

ther insured by providing the inside bores 19 and 23 of the boss 18 and follower 22 with annular sealing grooves 37 and 38 respectively. These grooves serve to catch particles of grease, which in their turn prevent the sea water from passing the same. Such of the grease as may work past the groove 38, must find its way out between the boss 18 and the therewith coacting recess in the hub of the propeller, but the amount of grease which passes off and is wasted is a negligible quantity.

The seal retainer at the inboard end of the stern tube E is here shown as consisting of a plate 15^a of substantially discoidal contour. This plate may be held in its assigned position up against the hereinbefore mentioned flange E⁷ by the same stud bolts E⁸, that heretofore were used to keep the common stuffing box gland in place. The interior of the said plate 15^a is hollowed out as at 21^a to provide a chamber within which is contained a follower 22^a driven by the forward end of the tail shaft F thru the instrumentality of a feather 24^a, while free for limited longitudinal movement thereon. In order to prevent the said follower 22^a from slipping back into the space formerly occupied by the fibrous packing, this follower is made larger than the internal diameter of the stuffing box ordinarily located at this point. A split ring 32^a wedgingly engaged by the follower 22^a is lodged within a forward recess of the latter and participates in its movements, being adapted to preclude straight outflow of the lubricant at the stern tube's forward extremity. The space immediately in rear of the follower 22^a fills up with grease and serves as a reservoir therefor, whereby the main flow is directed rearwardly. It is obvious that the grease that may work its way out thru the forward seal can be recovered and used over again. It will be noticed that both the key-means 24 and 24^a are located inwardly of the seats of their respective follower elements 22 and 22^a, the feather 24 being obviously disposed forwardly of the seat 26.

From the foregoing it will be apparent that the seal for either end of the stern tube can be applied thereto without requiring changes of any appreciable character. In practicing the present invention any desired lubricant may be employed, such for example as heavy oil or grease, and in the following claims, this lubricant is referred to generically as a fluid.

While a certain preferred embodiment of this device has been shown and described, it will be understood that changes in the form, arrangements, proportions, sizes and details thereof may be made, without departing from the scope of the invention as defined by the appended claims.

Having described my invention what I

desire to secure by Letters Patent and claim, is:-

1. A stern bearing for propeller shafts comprising in combination, a tube thru which the shaft passes provided with a closure forming a seat adjacent its outer end, an element associated with the shaft and said seat adapted to be impelled against the latter by fluid pressure within said tube to effect a seal precluding exit of the fluid or the entrance of sea water, key-means with the shaft capable of imparting coincidental rotation to said element, said key-means being disposed forwardly of the said seat so as to be protected thereby, and other means for introducing said fluid under pressure into the tube. 65
2. A stern bearing for propeller shafts comprising in combination, a tube in which the shaft is housed, a member closing the after end of said tube having direct engagement with the shaft, an element driven by said shaft mounted thereupon, being also capable of movement toward or away from said member, and means for introducing a fluid under pressure into the tube to lubricate the parts and to force said element into engagement with the member to effect a seal against leakage of the fluid or the entrance of sea water. 80
3. A stern bearing for propeller shafts comprising in combination, a tube in which the shaft is journaled, a closure for the outer end of said tube including a fixed seat, an annular element composed of parts rotated together by said shaft while capable of longitudinal movement thereupon, the ends of both of said parts being normally in contact with said seat, and means for introducing a lubricant under pressure into the tube to lubricate the working parts and forcing said element against the closure in order to effect a tight seal preventing escape of the lubricant or the entrance of sea water. 85
4. A stern bearing for propeller shafts comprising in combination, a tube thru which the shaft extends, a closure for the after end of said tube, a recessed element driven by said shaft axially movable thereupon toward or away from said closure, packing means lodged in said recess precluding leakage along the shaft, said packing means being also slidably upon and rotated by the latter, and means for introducing a fluid into the tube to lubricate the working parts and force said element into engagement with the closure to effect a seal against the exit of the fluid or the entrance of sea water. 100
5. A stern bearing for propeller shafts comprising in combination, a tube thru which the shaft passes, the latter carrying the propeller which is provided in the forward face of its hub with a recess, and means fixed to the end of said tube projecting into said recess in contact with the shaft to enclose the same. 115
6. A stern bearing for propeller shafts comprising in combination, a tube affording a lubricated bearing for the shaft, the latter carrying the propeller which is provided with a recess in the forward face of its hub, a closure for the after end of said tube attached thereto and having a boss taking over the shaft in position to extend into said recess, and means associated with said closure precluding exit of lubricant from the interior of the tube or entrance of sea water thereinto. 120
7. A sealing device for a propeller shaft stern tube comprising a retaining member provided with a recess affording a seat including transverse and circumferential surfaces, means for affixing said member endwise of said tube, a tightening element lodged in said recess and rotated directly by said shaft at the forward side of said seat and having a limited axial movement on the former, said element being in working engagement with both of said surfaces, and means within the tube for holding the element against the seat. 125
8. A sealing device for a propeller shaft stern tube including a chambered retaining member having a seat, means for securing said member to the end of said tube, a recessed element lodged in the chamber of the said member and rotated by said shaft being free to move longitudinally thereon relatively to said seat, a split packing ring contained in the recess of said element in position to rotate therewith in contact with the shaft, and means for pressing the joined element and packing ring against the seat to prevent leakage into or out of the tube. 130
9. A sealing device for a propeller shaft tube including a cap member secured to the latter, said member having a bore and provided with a transverse seat, a first collar slidably in said bore against said seat over the shaft, said collar being formed with an outwardly flaring recess facing the seat, a second collar fitted into said recess, said second collar being split to enable the same to tighten itself upon the shaft when the first named collar is moved thereagainst, a key-element for imparting rotation to the coacting collars from the shaft, and means within the tube acting to force the collars conjointly upon the seat in the member. 135

EDWARD ALLEN.
